UNITED STATES PATENT OFFICE.

THOMAS PRICE, OF NANAIMO, BRITISH COLUMBIA, CANADA.

FURNACE-GRAVE.

1,325,995.

Specification of Letters Patent. Patented Dec. 23, 1919.

Application filed May 7, 1919. Serial No. 295,347.

To all whom it may concern:

Be it known that I, THOMAS PRICE, a citizen of the Dominion of Canada, residing at Nanaimo, in the Province of British Columbia, Canada, have invented certain new and useful Improvements in Furnace Grates, of which the following is a specification.

This invention relates to a self-cleaning fire-grate for a boiler furnace or the like which has been particularly designed to enable a low grade fuel, carrying a high percentage in ash and clinker, to be used with elimination of the manual labor usually necessary to keep the fire bars clean and the fire bright.

The invention is particularly described in the following specification, reference being made to the drawings by which it is accompanied, in which:

Figure 1 is a plan of a double furnace showing the grate bars and the manner of connection of the operating mechanism to the alternate bars.

Figs. 2 and 3 show to an enlarged scale the rotatable grate bars in plan and in end elevation.

Figs. 4 and 5 show to a similarly enlarged scale the stationary grate bars in plan and cross section.

Fig. 6 is a detail showing the shaft on the divided parts of which the operative pawl wheels are mounted to independently operate the grate bars of separate boiler furnaces.

Fig. 7 is a side elevation and part section of the furnace and its operative mechanism.

Fig. 8 shows a section of the grate bars illustrating the alternate bars as rotatable.

Fig. 9 is a sectional face view to an enlarged scale of the pawl carrying head of the rotatable grate bars, and

Fig. 10 is a face view (and part section on the line 10—10 of Fig. 1) of the mechanism by which the power is applied to operate the bars of a series of furnaces providing for the variable movement which separate boilers may require, the near shaft bearing and pawl carrying plate being removed.

Fig. 11 is an edge view of the member described in Fig. 9.

The drawing shows the grate as applied

to a brick-lined furnace chamber, the products of combustion from which are delivered to the flues of a boiler. While this is preferable as affording an opportunity for more complete combustion, it is not an essential requirement as the grate may be applied to any furnace and the furnace applied to any purpose where furnace heat is required.

The grate consists of transversely disposed, alternate, fixed and revolving grate bars 2 and 3. The ends of these bars are carried on bearer plates 4 along each side, which are provided with seats for the fixed bars 2 and half bearings for the revolving bars 3. The fixed bars are of the herringbone type having interspaces acutely angled in opposite directions along each edge from the lengthwise ribs and between the ribs the interspaces are disposed across at right angles.

The rotatable bars 3 are formed with a square central stem which is rounded at each end where it seats in the bar bearer 4 and at one end is produced beyond the bearer bar 4 to pass through the side wall of the furnace and is squared to receive the mechanism by which they are rotated.

Intermediate of the bearers 4 each bar 3 has a series of interspaced square flanges, the flats of which correspond with the level of the fixed bars 2 when in place.

On the squared end of each rotatable bar 3 is secured a star ratchet wheel 5 and mounted free on each side of the ratchet wheel and connected together are plates 6 which carry between them the ratchet pawls 7.

A connecting bar 9 extends along each side of the double furnace, and is connected to a pin 8 secured between the upper ends of each pair of pawl plates 6 that the plates may be simultaneously oscillated from the arm 11 of a rocking shaft 10, which is mounted in bearings across one end of the furnace chamber. This rocking shaft 10 thus oscillates the grate bars of both furnaces and is itself oscillated by any suitable means.

Where a battery of boilers is in one installation they are preferably arranged in pairs and to enable the condition of the fire of the several boilers to be separately regu-

lated, the arm 12 of the rocking shaft is connected by a rod 13 to a pin 14 which is adjustable in a radial slot 15 of a crank disk 16. This crank disk is secured on the end 5 of a shaft 17 which is endwise divided and the end of one part socketed in the end of the other, see Fig. 6, that the two parts are independently rotatable.

On each divided part of this shaft 17 is 10 secured a ratchet wheel 18 on which is mounted a pair of plates 19 carrying between them a pawl 20. A check pawl 21 is also mounted in the foundation frame which carries the bearings of the shaft, etc., 15 and prevents rotation backward. To a pin secured between the produced lower ends of the pawl carrying plates 19 of each ratchet wheel 18 is connected a rod 22 from separate eccentrics 23 secured on a shaft 24, 20 which shaft is driven by an endless chain 25 over a sprocket wheel 26 from any convenient source of power.

With this mechanism, rotation of the shaft 24 by the chain 25 imparts, by means of the 25 eccentrics 23, an oscillating movement to the pawl carrying plates 19 and through them a periodic rotational movement to each part of the shaft 17 and their crank disks 16. Through the radially adjustable crank pins 30 14 of these disks, an oscillating movement is imparted for each revolution of the shaft 24, to the rocking shafts 10 of adjacent boilers and therefrom through the connecting bars 9 to the rotatable grate bars 3, 35 imparting to them a periodic, slowly, rotatable movement.

The amount of this movement may be regulated by the position of the pin 14 in the radial slot 15 of the crank disk, but to 40 enable this variation to be made for the furnaces of one boiler, while the mechanism is in motion, and without disturbing that of the others, a pawl fence 30 is adjustable in a curved slot 31 to be circumferentially 45 movable concentric with the ratchet wheel 18. This fence 30 is set close to the ratchet teeth and may be adjusted to lift the pawl from contact with any desired number of teeth while the oscillating plates move 50 through their full movement, the pawl riding the fence over the teeth it is desired to cut out.

The effect of the rotation of the square flanged grate bar in lifting and lowering the 55 fuel, and at the same time dragging it forward from the fire door, effectually frees that fuel from the dust, which dust falls through the bars, and as the square flanged bars rotate the clinker is free to fall into the ash 60 pit. As the movement of the alternate bars is in one direction, they are also effective in dragging the clinker from the fixed bars.

Having now particularly described my invention, I hereby declare that what I claim

as new and desire to be protected in by 65 Letters Patent, is:

1. A furnace grate, comprising the combination with a furnace chamber, of fixed and rotatable grate bars spaced alternately across the chamber, said rotatable bars having 70 rectangular flanges interspaced on a central core, and means for imparting a rotational movement to the alternate bars.

2. A furnace grate, comprising the combination with a furnace chamber, of fixed and 75 rotatable grate bars spaced alternately across the chamber, the fixed bars having lengthwise webs with air spaces across between them and acutely angled air spaces from the webs outward to each edge of the 80 bar, and the rotatable bars having square flanges interspaced on a central core, and means for imparting a rotational movement to the alternate bars.

3. A furnace grate, comprising the combination with a furnace chamber, of fixed and rotatable grate bars spaced alternately across the chamber, a ratchet wheel secured on the end of each rotatable bar, a pawl 85 mounted to move concentric with and to engage the teeth of the ratchet wheel, a connecting bar pin-connected to the pawl carrying means of each rotatable grate bar, said rotatable bar having squared flanges interspaced on a central core and means for imparting 90 a reciprocating movement to the connecting bar.

4. A furnace grate, comprising the combination with a furnace chamber, of fixed and rotatable grate bars spaced alternately 100 across the chamber, a ratchet wheel secured on the end of each rotatable bar, a pawl mounted to move concentric with and to engage the teeth of the ratchet wheel, a bar pin-connected to the pawl carrying means of 105 each rotatable grate bar, a shaft rotatable at a substantially constant velocity, an eccentric crank pin secured on said shaft, means for connecting the crank pin to pawl carrying plates mounted to move freely concentrically 110 with a second shaft parallel with that on which is the pin, a ratchet wheel secured on the second shaft between the pawl carrying plates, and a crank with a radially adjustable crank pin secured on the second shaft, 115 which pin is connected to the reciprocating rod of the grate bars.

5. A furnace grate, comprising the combination with a furnace chamber, of fixed and rotatable grate bars spaced alternately 120 across the chamber, a ratchet wheel secured on the end of each rotatable bar, a pawl mounted to move concentric with and to engage the teeth of the ratchet wheel, a bar pin-connected to the pawl carrying means of 125 each rotatable grate bar, a shaft rotatable at a substantially constant velocity, an eccentric crank pin secured on said shaft, means

for connecting the crank pin to pawl carrying plates mounted on a second shaft parallel to the first named to move concentrically with a ratchet wheel secured on the second shaft, a crank with a radially adjustable pin secured on the second shaft, which pin is connected to reciprocate the connecting rod of the rotatable grate bars, a fence

movable concentrically with the ratchet wheel of the second shaft with means for 10 moving the fence circumferentially to interpose it between the pawl and any desired number of teeth of the ratchet wheel.

In testimony whereof I affix my signature.

THOMAS PRICE.
